UNITED STATES PATENT OFFICE.

CARL HÜLSTER, OF NEW YORK, N. Y.

DESIGN FOR FUR CLOAKS.

Specification forming part of Design No. 7,455, dated May 26, 1874; application filed May 2, 1874.
[Term of Patent 7 years.]

To all whom it may concern:

Be it known that I, CARL HÜLSTER, of New York city, county and State of New York, have invented a Design for Fur Cloaks, of which the following is a specification:

The nature of my design is fully represented in the accompanying drawing, to which reference is made.

A represents the body of the cloak, and B the trimmings or ornaments of the cloak in front. C represents the trimmings or ornaments on the back of the cloak. The trimmings or ornaments B in front consist of parallel horizontal stripes placed at certain intervals in front of the cloak from the throat downward between two vertical curved borders running from the lower part of the front upward over the shoulders and down the back in curved lines C C farther apart at the bottom. The lower part of the cloak is trimmed

or ornamented with a border, d, and at the sides with trimmings e e, representing pockets, extending from the horizontal stripe B'. F are trimmings or ornaments in front of the arms G. H is a border around the lower part of the arms G. J is a trimming, representing the collar.

I prefer to make the body white and the stripes or ornaments black, or of mixed black and white; but I do not consider the colors selected to be an essential element in my design.

What I claim as my invention is—

The design for fur cloaks, substantially as herein shown and described.

CARL HÜLSTER.
